Specification for Design.

Patented Sept. 7, 1920

Application filed May 1, 1920. Serial No. 378,301. Term of patent 14 years.

To all whom it may concern:

Be it known that I, MARTIN T. GRAF, a citizen of the United States, residing at Buffalo, in the county of Erie and State of New York, have invented a new, original, and ornamental Design for a Sharpener for Knives, of which the following is a specification, reference being had to the accompanying drawing, forming part thereof.

Figure 1 is a side view of a sharpener for knives showing my new design. Fig. 2 is an end view of the same.

I claim:

The ornamental design for a sharpener for knives, as shown.

MARTIN T. GRAF.
